(57) **CLAIM**

The ornamental design for a film-transferring device for office use, as shown and described.

DESCRIPTION

FIG. 1 is a plan view showing my new design for a film-transferring device for office use;

FIG. 2 is a front elevation view thereof;
FIG. 3 is a cross-sectional view taken in the direction of arrows 3—3 in FIG. 1;
FIG. 4 is a left side elevational view thereof;
FIG. 5 is a right side elevational view thereof;
FIG. 6 is a bottom view thereof;
FIG. 7 is a rear elevational view thereof;
FIG. 8 is a cross-sectional view taken in the direction of arrows 8—8 in FIG. 2;
FIG. 9 is a cross-sectional view taken in the direction of arrows 9—9 in FIG. 2;
FIG. 10 is a front elevational view in an in-use position with the cover member folded back, the ground line being shown for illustrative purposes only and forming no part of the claimed design;
FIG. 11 is a top plan view of the body portion shown separately for each of illustration;
FIG. 12 is a front elevational view of FIG. 11;
FIG. 13 is a left side elevational view of FIG. 11;
FIG. 14 is a right side elevational view of FIG. 11;
FIG. 15 is a bottom plan view of FIG. 11;
FIG. 16 is a rear elevational view of FIG. 11;
FIG. 17 is a cross-sectional view taken in the direction of arrows 17—17 in FIG. 11;
FIG. 18 is a cross-sectional view taken in the direction of arrows 18—18 in FIG. 12;
FIG. 19 is a top plan view of the tape cassette portion shown separately for each of illustration;
FIG. 20 is a front elevational view of FIG. 19;
FIG. 21 is a cross-sectional view taken in the direction of arrows 21—21 in FIG. 20;
FIG. 22 is a bottom plan view of FIG. 19;
FIG. 23 is a rear elevational view of FIG. 19;
FIG. 24 is a left side elevational view of FIG. 19;
FIG. 25 is a right side elevational view of FIG. 19;
FIG. 26 is a cross-sectional view taken in the direction of arrows 26—26 in FIG. 19;
FIG. 27 is a cross-sectional view taken in the direction of arrows 27—27 in FIG. 20;
FIG. 28 is a perspective view of FIG. 1;
FIG. 29 is a perspective view of FIG. 11; and,
FIG. 30 is a perspective view of FIG. 19.
